(57) **CLAIM**

We claim the ornamental design for a case for mobile telephone, as shown and described.

DESCRIPTION

FIG. 1 is a front perspective view of a case for mobile telephone showing our new design in accordance to a first embodiment;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a cross-sectional view taken along the line 9-9 of FIG. 2;

FIG. 10 is a front perspective view of the case for mobile telephone in which a mobile telephone is provided in broken lines to illustrate an example state of use;

FIG. 11 is a front perspective view of a case for mobile telephone showing our new design in accordance to a second embodiment;

FIG. 12 is a front view thereof;

FIG. 13 is a rear view thereof;

FIG. 14 is a left-side view thereof;

FIG. 15 is a right-side view thereof;

FIG. 16 is a top view thereof;

FIG. 17 is a bottom view thereof;

FIG. 18 is a rear perspective view thereof;

FIG. 19 is a cross-sectional view taken along the line 19-19 of FIG. 12; and,

FIG. 20 is a front perspective view of the case for mobile telephone in which a mobile telephone is provided in broken lines to illustrate an example state of use.

The broken lines shown in the figures illustrate portions of the case for mobile telephone which form no part of the embodiment in which they are shown.

(Continued)

The broken lines shown in FIGS. 10 and 20 illustrate the environment of a mobile telephone and form no part of the embodiment in which they are shown.
